UNITED STATES PATENT OFFICE.

JOSEPH G. KAEMPFER, OF NEW YORK, N. Y.

DESIGN FOR A DOLL-HEAD.

45,093.

Specification for Design.

Patented Dec. 30, 1913.

Application filed September 20, 1913. Serial No. 790,961. Term of patent 3½ years.

To all whom it may concern:

Be it known that I, JOSEPH G. KAEMPFER, a citizen of the United States, residing in the city of New York, in the county and State of New York, have invented a new, original, and ornamental Design for Doll-Heads, of which the following is a specification, reference being had to the accompanying drawings, forming part thereof.

The figure is a perspective view of a doll head showing my new design.

I claim:

The ornamental design for a doll head, as shown.

JOSEPH G. KAEMPFER.

Witnesses:

MAURICE L. SHARUE,
JOSEPH L. GOODMAN.
